UNITED STATES PATENT OFFICE.

FRANCIS J. COLE AND FRANK F. SCOVILLE, OF SCHENECTADY, NEW YORK.

LOCOMOTIVE TRAILING TRUCK.

1,189,793.

Specification of Letters Patent. Patented July 4, 1916.

Application filed May 5, 1916. Serial No. 95,522.

To all whom it may concern:

Be it known that we, FRANCIS J. COLE and FRANK F. SCOVILLE, both of Schenectady, in the county of Schenectady and State of New York, have jointly invented a certain new and useful Improvement in Locomotive Trailing Trucks, of which improvement the following is a specification.

Our invention relates to trailing trucks for locomotive engines, of the hinged floating yoke type, instances of which are exemplified in Letters Patent of the United States Nos. 936,413 and 991,139, granted and issued to us under dates of October 12, 1909 and 15 May 2, 1911, respectively.

The object of our present invention is to provide, in a trailing truck of the type referred to, means whereby the height of the spring carrying seats may be reduced, as well as simple, convenient and desirable means for connecting the friction plates with the floating yokes.

The improvement claimed is hereinafter fully set forth.

In the construction of Patent No. 936,413 aforesaid, the connection between the yoke, the spring seat, and the friction plates was effected through toggle joints, and in that of Patent No. 991,139, through spherical bearings. In each of these designs, friction plates are provided, below and above the toggles or spherical bearings, so that the carrying springs were raised so high that it was often found difficult to obtain the necessary clearance between their ends and the firebox foundation ring. Under our present invention, the yokes are disposed entirely outside the springs, and connected thereto by hinged joints, cylindrical bearings being interposed between the spring seats and friction plates. It is thereby made practicable to effect a considerable reduction in the heights of the springs, by the resultant reduction of distance between the tops of the journal boxes and the spring bands. The hinged connections of the spring seats and yokes provide for the rise and fall of the locomotive transversely, and the cylindrical bearings on the bottoms of the spring seats and corresponding recesses in the friction plates, accommodate longitudinal angularity, so that the friction plates, at all times, bear fully and solidly on the tops of the journal boxes.

In the accompanying drawings: Figure 1 is a half plan or top view of a locomotive

trailing truck illustrating an embodiment of our invention; Fig. 2, a side view, in elevation; Fig. 3, a half rear end view; Fig. 4, a plan view, on an enlarged scale, showing the hinged connection between the spring seat and the floating yoke; Fig. 5, a side view, in elevation, of the same; Fig. 6, a vertical transverse section on the line α α of Fig. 5; Fig. 7, a plan view of the spring seat; and, Fig. 8, a transverse section through the spring seat and sliding plate on which it rests.

In general construction, and except as to the novel features constituting our present invention, our improved trailing truck accords, in all substantial particulars, with those set forth in Letters Patent Nos. 936,413 and 991,139 aforesaid, and therefore said novel features only will be herein fully and at length described.

In the practice of our invention, referring descriptively to the specific embodiment thereof which is herein exemplified, the truck axle, 3^a, upon which the truck wheels, 3, are secured, is, as in Letters Patent Nos. 936,413 and 991,139, provided with outside journals, which rotate in bearings fitted in journal boxes, 69, in the usual manner, said journal boxes being fixed in the side frame members, 65, of the truck. The rear frame members, 8^a, of the locomotive, are supported upon the truck axle through the intermediation of springs, 42, the bands, 42^a, of which are seated upon the tops of the journal boxes, 69, means which constitute a leading and characteristic feature of our present invention, and which will now be described, being interposed between the spring bands and journal boxes. By the application of said means, the operative results of universal adjustment of the springs and journal boxes which are attained by the constructions set forth in Patent Nos. 936,413 and 991,139, are, under our present invention, provided, with the further advantages of a reduction in the height of the springs and a more desirable system of connection.

Floating yokes, 50, extend longitudinally below the springs, 42, and are coupled, at their ends, to the rear main frame members, 8^a. Intermediate of their ends, they are coupled by universal joint connections, embodying our present invention, to the springs, 42, and journal boxes, 69. The yokes, 50, are located entirely outside the springs, instead of below them as in Pat-

ents Nos. 936,413 and 991,139, and the spring bands, 42^a, are supported on spring seats, 42^c, having eyes on their outer sides to receive longitudinally extending horizontal bolts, 51, by which they are hinged to the yokes. The bottoms of the spring seats, 42^c, are in the form of longitudinally curved or segmental bearings, 42^f, which fit in correspondingly curved recesses in friction plates, 81, said plates, in turn, being seated on the tops of the journal boxes. The universal joints which are provided in a transverse vertical plane by means of the hinges outside of the spring seats, and the curved bottoms of the spring seats permit movement in a longitudinal vertical plane. Movement in a transverse plane is provided for by the support of the friction plates, 81, on the tops of the journal boxes.

20 Oil cups, 42^e, are fixed to the tops of the floating yokes, adjacent to the spring seats, and oil passages, 42^h, extend therefrom to the faces of the curved bearings, 42^f, of the spring seats.

25 We claim as our invention and desire to secure by Letters Patent:

1. In a locomotive engine, the combination of a main frame; a radial truck pivoted thereto; springs through which weight borne by the main frame is transmitted to the journal boxes of the truck; floating yokes pivoted at the ends to the main frame and extending intermediately on the outer sides of the springs; and spring seats hinged to the floating yokes and interposed between the springs and the truck journal boxes.
2. In a locomotive engine, the combination of a main frame; a radial truck pivoted thereto; springs through which weight borne by the main frame is transmitted to the journal boxes of the truck; floating yokes pivoted at their ends to the main frame and extending intermediately on the outer sides of the springs; spring seats

hinged to the floating yokes; and segmental bearings on said seats through which they are supported on the truck journal boxes.

3. In a locomotive engine, the combination of a main frame; a radial truck pivoted thereto; springs through which weight borne by the main frame is transmitted to the journal boxes of the truck; floating yokes pivoted at their ends to the main frame and extending intermediately on the outer sides of the springs; friction plates resting on the truck journal boxes; spring seats hinged to the floating yokes; and segmental bearings on said seats fitting corresponding recesses in the friction plates.

4. In a locomotive engine, the combination of a main frame; a radial truck pivoted thereto; springs through which weight borne by the main frame is transmitted to the journal boxes of the truck; floating yokes pivoted at their ends to the main frame and extending intermediately on the outer sides of the springs; spring seats on which the bands of the springs are supported and having eyes on their outer sides; hinge bolts passing through said eyes and coupling the spring seats to the yokes; and segmental bearings on the spring seats, which are curved in planes parallel with the hinge bolts and through which said seats are supported on the truck journal boxes.

5. A spring seat for radial trucks of locomotive engines having a recess in its top adapted to receive a spring band and a longitudinally extending hinge bolt eye, and having a segmental bearing on its bottom which is curved in a plane parallel with the axis of the hinge bolt eye.

FRANCIS J. COLE.
FRANK F. SCOVILLE.
